US00D929421S

(12) **United States Design Patent** (10) **Patent No.:** **US D929,421 S**
(45) **Date of Patent:** **** Aug. 31, 2021**

(54) **DISPLAY PANEL WITH NEWS HEADLINES
GRAPHICAL USER INTERFACE**

(71) Applicant: **Facebook, Inc.**, Menlo Park, CA (US)

(72) Inventors: **Joseph Rhyu**, New York, NY (US);
Riccardo Carlet, Brooklyn, NY (US);
Alessandra Villaamil, Brooklyn, NY (US)

(73) Assignee: **Facebook, Inc.**, Menlo Park, CA (US)

(**) Term: **15 Years**

(21) Appl. No.: **29/711,052**

(22) Filed: **Oct. 28, 2019**

(51) LOC (13) Cl. **14-04**

(52) U.S. Cl.

USPC **D14/485**

(58) **Field of Classification Search**

USPC **D14/485-495**

(57) **CLAIM**

The ornamental design for a display panel with news headlines graphical user interface, as shown and described.

DESCRIPTION

FIG. 1 is a front view of a display panel with news headlines graphical user interface, according to a first embodiment. FIG. 2 is a front view of a display panel with news headlines graphical user interface, according to a second embodiment; and,

FIG. 3 is a front view of a display panel with news headlines graphical user interface, according to a third embodiment. The outermost broken lines in the drawings illustrate an electronic device and are included for the purpose of illustrating the environment of the design and form no part of the claimed design. The remaining broken lines illustrate portions of the graphical user interface that form no part of the claimed design.

1 Claim, 3 Drawing Sheets
